UNITED STATES PATENT OFFICE

2,007,794

ELECTRICALLY LIGHTED SEWING
MACHINEJames W. Dawson, Belvidere, Ill., assignor to
National Sewing Machine Company, Belvidere,
Ill., a corporation of Illinois

Application August 20, 1934, Serial No. 740,543

2 Claims. (Cl. 240—2.14)

This invention relates to improvements in electrically lighted sewing machines.

One of the objects of my invention is to efficiently illuminate the material to be worked upon.

Another object is to provide simple and efficient means for mounting the lamp in the face plate of the sewing machine arm so as to be readily accessible in case it is desired to remove the lamp or the lamp and socket.

Another object is to provide an electric lamp and socket which may be mounted within the hollow face plate of the sewing machine arm and which may be removed as a unit without disturbing the wiring for conveying electric current to the socket and lamp.

Heretofore wiring for carrying current to the lamp has been permanently connected to the lamp socket, and in the event either required removal it was necessary to make a new connection of socket to wiring at the machine. By the construction herein described the objections to prior art constructions are avoided and the advantages of easy assembly and repair are gained.

Other objects and advantages will be apparent from the following specification.

In the drawing:

Figure 1 is a longitudinal vertical section of part of the overhanging arm of a sewing machine including the face plate.

Figure 2 is an end elevation of the sewing machine arm with the face plate removed.

Figure 3 is a horizontal sectional view taken on the line 3—3 of Figure 1.

In that embodiment of my invention which I have chosen to illustrate in the drawing, the overhanging arm of the sewing machine is indicated at 10 and the hollow face plate at 11. The plate 11 is detachably secured to the edges 12 of the

walls of the arm by screws (not shown) or any suitable means. The bottom wall 13 of the arm is provided with openings 14 to accommodate the presser foot bar and needle shaft (not shown).

The chamber within the arm 10 for holding the needle operating mechanism is separated from the space within the hollow face plate 11 by a flat plate 15 secured by screws 16, 16, at top and bottom, to thickened portions 17 of the arm 10.

The plate 15 supports the means for conducting current to the lighting device, said means comprising lead wires 18, 18, which extend through an aperture 19 in the plate 15, to screws 20, 20 which secure the end of each wire to a bus bar 21 in electrical contact therewith. The bus bars 21, 21 are insulated from the plate 15 by insulation

22 and are fastened by rivets 23, in parallel spaced positions, to the insulated plate 15. Each bus bar 21 carries a contact member 24. The contacts 24 extend at right angles to the plate 15, and have parallel contact faces spaced apart to engage between them the socket 25.

The socket 25 comprises a cylindrical body having the upper portions of opposite sides cut away and flattened at 26 for engagement by the contacts 24. The lower end of the socket is adapted to receive the screw threaded end of a conventional electric lamp 27. Above the cylindrical body of the socket is a centrally located screw threaded pin 28 adapted to extend through an opening in a bracket 29 integral with the hollow face plate 11. A nut 30 is screwed on the pin 28 to connect the socket to the face plate.

In assembling the parts, the wiring 18 may be conveniently attached to the bus bars 21 for conveying current to the contacts 24, and the plate 15 may be readily secured in position on the arm 10. The socket 25 and lamp 27, mounted in the hollow face plate 11, are brought into electrical connection with the source of current, through engagement with the contacts 24 between which the socket is positioned when the hollow face plate is secured in its intended position on the arm 10.

The inner surface of the face plate 11 will be finished to serve as a reflector for the lamp which is entirely concealed within the hollow face plate and separated from the mechanism in the overhanging arm 10.

Changes may be made in details of construction without departing from the scope of my invention and I do not intend to be limited to the exact form of construction herein shown and described except as set forth in the appended claims.

I claim as my invention:

1. An electrically lighted sewing machine comprising a longitudinally extending arm, a presser foot and needle bar mounted in the arm, a hollow face plate detachably mounted on the end of the arm to form an end wall and portions of the side walls of the arm and having a bottom opening adjacent the presser foot and needle bar but spaced longitudinally of the arm from said presser foot and needle bar, an electric light socket and lamp carried by and located within the hollow face plate, means for conveying electrical current to the socket, said means comprising a supporting plate secured to the arm walls between the arm and face plate, electrical contact members on the supporting plate

extending toward the end wall of the hollow face plate to engage opposite sides of the lamp socket, and electrical wiring in the arm connected through said supporting plate to the contact members, said supporting plate extending transversely of the arm and separating the interior of the arm from the interior of the hollow face plate.

2. An electrically lighted sewing machine comprising a longitudinally extending arm, a presser foot and needle bar mounted in the arm, a hollow face plate and integrally formed bracket detachably mounted on the end of the arm to form an end wall and portions of the side walls of the arm and having a bottom opening adjacent the presser foot and needle bar but spaced longitudi-

nally of the arm from said presser foot and needle bar, an electric light socket and lamp carried by said bracket and located within the hollow face plate, means for conveying electrical current to the socket, said means comprising a supporting plate secured to the arm walls between the arm and face plate, electrical contact members on the supporting plate extending toward the end wall of the hollow face plate to engage opposite sides of the lamp socket, and electrical wiring in the arm connected through said supporting plate to the contact members, said supporting plate extending transversely of the arm and separating the interior of the arm from the interior of the hollow face plate.

JAMES W. DAWSON.
